UNITED STATES PATENT OFFICE.

ROBERT W. WIEDERWAX, OF ATLANTIC CITY, NEW JERSEY, ASSIGNOR OF ONE-HALF
TO CARLTON GEIST, OF ATLANTIC CITY, NEW JERSEY.

HEATING OR WELDING DEVICE.

1,263,979.

Specification of Letters Patent. Patented Apr. 23, 1918.

Application filed October 31, 1917. Serial No. 199,510.

To all whom it may concern:

Be it known that I, ROBERT W. WIEDERWAX, a citizen of the United States, residing at Atlantic City, in the county of Atlantic and State of New Jersey, have invented 5 certain new and useful Improvements in Heating or Welding Devices, of which the following is a specification.

The present invention relates to apparatus 10 for heating castings or the like, and retaining the same at a proper temperature, while being welded, but not necessarily restricted to this use.

An important object of the invention is 15 to provide apparatus of the above mentioned character, embodying a table upon which the castings or the like to be welded, are placed before or during the heating process, and having means for gradually 20 and uniformly heating, and cooling the castings, upon the table, to prevent cracking or distortion thereof.

A further object of the invention is to 25 provide apparatus of the above mentioned character, which is simple in construction, inexpensive to manufacture, strong and durable.

A further object of the invention is to 30 provide means for accurately controlling the temperature of the apparatus, during the heating or cooling periods.

Other objects and advantages of the invention will be apparent during the course 35 of the following description.

In the accompanying drawings forming a part of this specification and in which like numerals are employed to designate like parts throughout the same,

Figure 1 is a perspective view of apparatus embodying my invention, and,

Fig. 2 is a central vertical transverse sectional view through the same.

In the drawings, wherein for the purpose of illustration is shown a preferred embodiment of my invention, the numeral 5 designates a horizontal open frame, included in the top of a table. This frame comprises preferably metallic horizontal side strips 6, and spaced top and bottom metallic strips 45 7 and 8. This metallic frame has connection, at its corners with preferably metallic legs 9, form L-shaped in cross-section, as shown.

The metallic frame, constituting the top 50 of the table is filled with a refractory heat

absorbing and radiating material 10, such as silica or other material. The top metallic strips 7 are arranged above the upper surface of the heat absorbing and radiating material 10, and thus serve to prevent the 60 castings from contacting with the same.

The numeral 11 designates a top or cover, preferably including a metallic frame 12, to which is secured a sheet metal top 13 and sides 14. This top may be formed of any 65 other suitable material. The top has its lower end open and is adapted to be moved downwardly into contact with the table top.

Means are provided to raise and lower 70 the top or cover 11, and retain the same in the desired elevated position, comprising a cable 14', attached to the central portion of the top or cover, as shown at 15. This cable is passed about pulleys 16, pivoted to 75 suitable fixed supports (not shown). The cable 14' has connection with a weight 17, adapted to retain the top or cover 11 in the desired vertical position, when moved thereto.

The heating means for the apparatus includes a plurality of burners 19 of the Bunsen type. These burners are arranged beneath the top of the table and have tips 20, preferably discharging the flame upon 80 the heat absorbing and radiating element 10, between the strips 11. The burners 19 have means 21 to properly mix air and gas, and these burners are provided with cut off valves 22, controlling the supply of gas 85 from a pipe 23. This pipe is preferably secured to the legs 9 by brackets 24 or the like.

The operation of the apparatus is as follows:

The castings or the like, to be heated and welded, are placed upon the metallic strips 7 of the top of the table, and the top or cover 11 is moved to the lower closed position, to contact with the top of the table. 100 It is thus apparent that the casting is entirely surrounded or inclosed so that it cannot contact with currents of air. A suitable number of the burners 19 are set into operation, which serve to heat the heat absorber 105 or radiating element 10 which in turn radiates its heat in a gradual and uniform manner, to the casting or castings.

The welding operation may take place upon the top of the table or the castings 110

may be removed therefrom, during the welding operation. The welding may be effected by the ordinary acetylene welding torch, while the castings are supported upon the table, and the cover 11 is elevated. During this operation, the burners may be operating, thus retaining the table top at a suitable temperature, which is transmitted to the castings, so that they are retained at a proper temperature, while being welded.

When it is desired to gradually cool the castings subsequent to their welding and to prevent distortion or cracking, they are placed upon the top of the table and the lid or cover 11 is returned to the closed position, thus serving to hold the heat in proximity to the castings, and protect the same from currents of air. The burners 19 are cut off and the element 10 gradually gives up its heat to the casting and the surrounding atmosphere, whereby the casting cools gradually.

It is to be understood that the form of my invention herewith shown and described is to be taken as a preferred example of the same, and that various changes in the shape,

size, and arrangement of parts may be resorted to without departing from the spirit of the invention or the scope of the subjoined claim.

Having thus described my invention, I claim:

In an apparatus of the character described, a metallic table comprising an approximately flat open frame top, having upper spaced substantially horizontal strips and legs depending from the frame top, a filling of silica for the frame top arranged in a plane beneath the metallic strips, whereby castings are supported in spaced relation to the silica to prevent fusing, a cover to move downwardly in proximity to the frame top, and a plurality of gas burners supported near and beneath the frame top to heat the silica.

In testimony whereof I affix my signature in presence of two witnesses.

ROBERT W. WIEDERWAX.

Witnesses:

THEO W. SCHUUFF,
EMMA H. YARD.
